UNITED STATES PATENT OFFICE.

GEORGE C. BEIDLER, OF ROCHESTER, NEW YORK.

PHOTOGRAPHING AND DEVELOPING APPARATUS.

1,222,597.

Specification of Letters Patent. Patented Apr. 17, 1917.

Application filed June 11, 1914. Serial No. 844,516.

To all whom it may concern:

Be it known that I, GEORGE C. BEIDLER, a citizen of the United States of America, and resident of Rochester, in the county of Monroe and State of New York, have invented 5 certain new and useful Improvements in Photographing and Developing Apparatus, of which the following is a specification.

This invention relates to photographing 10 and developing apparatus and particularly to that type of apparatus embodying means for exposing film to light, severing the portion of the film exposed after it is mechanically drawn from the means for exposing it 15 to light, the cutting of the exposed portion of the film from the remainder of the film web, and means for developing the section of the film exposed.

An object of the present invention is to 20 provide means for delivering an exposed section of film to a receptacle which may contain fluid adapted to act on the coated surface of the film, such as developing solution, and novel means for drawing the film from 25 the said receptacle and for severing the same; the invention furthermore consisting in means for subjecting the developed film to the action of a fluid contained in another receptacle to which the film is delivered 30 after it is removed from the first receptacle, novel means being provided for submerging the film therein to insure proper contact of the liquid with the said film and for other 35 purposes, all of which mechanism is preferably contained within a light-proof casing, capable of excluding actinic rays of light, during the time the mechanism is operating for treating the film.

A further object of this invention is to 40 provide novel means for subjecting film to the action of fluid, the provision of means for submerging the film, the provision of means for cutting the film, said means being correlated and associated to effect the development of an exposed film mechanically 45 while the said film is guarded from light.

With the foregoing and other objects in view, the invention consists in the broad idea to be set forth in the claims during the 50 prosecution of the application, the said claims to be of such scope as to give protection commensurate with the inventive act in view of the state of the art when the said invention was produced.

In describing the invention in detail, reference will be had to the accompanying

drawings forming part of this specification wherein like characters denote corresponding parts in the several views and in which—

Figure 1 illustrates a view in elevation of 60 a casing showing the operating handles, a gage for the light guard, and means associated therewith, the supports for the case being omitted;

Fig. 2 illustrates a vertical sectional view 65 of the apparatus shown in Fig. 1, a portion thereof being shown in elevation;

Fig. 3 illustrates a transverse sectional view of the apparatus;

Fig. 4 illustrates an enlarged detail sec- 70 tional view of a fragment of the casing;

Fig. 5 illustrates a perspective view of a movable knife and means for carrying the knife, and a guard associated therewith;

Fig. 6 illustrates a perspective view of a 75 fragment of a guide for parts of the mechanism;

Fig. 7 illustrates a perspective view of a 80 rod carrying block with a fragment of the rod shown detached therefrom;

Fig. 8 illustrates a perspective view of the said block from the opposite side illustrating a fragment of the conveyer chain for moving the said block;

Fig. 9 illustrates a side elevation of a link 85 forming a part of a submerging apparatus;

Fig. 10 illustrates a side elevation of the parts shown in Fig. 9 in different positions of adjustment;

Fig. 11 illustrates a side elevation of a 90 conveying chain associated with means for operating the same;

Fig. 12 illustrates a plan view of the gearing for operating the conveyer chains.

In these drawings, I have shown an in- 95 closure divided into several compartments but the manner of forming the compartments is not material and may be changed to suit particular requirements. In the present embodiment of the invention, I have 100 shown a magazine section 20 and a receptacle casing 21, the latter of which is provided with a door 22, hinged at 23, so that access to the interior of the receptacle cas- 105 ing may be facilitated and the said receptacle casing may be further provided with a hinged end 24.

The receptacle casing is shown as having longitudinally disposed partitions 25 near the sides thereof, the said partitions forming compartments 26 adapted to contain 110 operating mechanism which is preferably

2
constructed of metal so that the said partitions act as shields for these metal parts and protect them against chemicals which are used in the development or fixing of the film.

The inner surface of each side of the receptacle casing has a substantially F-shaped guide 27 secured to it and an angle bracket is furthermore secured to the guide plate 10 producing the double guides 29 and 30 for a purpose to be presently explained. The partitions 25 have slots 31 horizontally disposed and extending longitudinally to form ways for the passage therethrough of blocks 15 33 and 34, slidable on the guides 30, it being observed that the said blocks have slots 34^a forming clearances for the reception of the said guides. Each block is provided with a socket 35 to receive the trunnion 36 on the 20 rod 32 so that said rod may rotate, although the rotary action is not essential to its operation. The purpose of the rod is to engage and pull film from a receptacle.

As a means for moving the blocks longitudinally of the guides, each block has a 25 socket 37 which receives a stud 38 forming a continuation of one of the link pins 39 of the chain 40, and, therefore, movement of the chain of each block, results in moving 30 the block. The guides 30 act as supports for the chains in their travel longitudinally of the casing.

A receptacle 41 extends through the bottom of the casing 21 and is supported or suspended by any appropriate means as by the angle irons 42 and the said receptacle is adapted to contain fluid which will act on the coated surface of the film, after it has been exposed to light and in most instances, 35 the said receptacle is used as a container for developing fluid. At a point above the receptacle 41 or in such position that film may be delivered to the receptacle by their action, are film drawing rolls 43 and 44 which 40 may be journaled in any appropriate way in the casing, one of said drawing rolls, preferably the drawing roll 43 having a shaft 45 extending beyond the casing and having a crank handle 46 applied to it so that the 45 said roll may be turned and as the peripheries of the said rolls are practically in contact under normal conditions and are adapted to bear against the surface of film when they are caused to coact for the purpose of 50 drawing the film, the said rolls operate to draw film from the magazine 20 so that said film may be delivered to the receptacle 41.

The magazine 20 has a front wall 47 55 which constitutes a backing for the film, which is drawn over the anti-friction roller 48, journaled near the top of the mechanism, and the film is caused to travel over said anti-friction roller and down into the casing 21 containing the receptacle 41.

That portion of the magazine in front of the wall 47 constitutes an exposing chamber in which the film is subjected to the action of light which may be admitted through the bellows 49 and the bellows frame 50, which latter is fitted to the front portion of the magazine or an extension thereof. The dark slide 51 which may move transversely of the exposing chamber is of a type ordinarily employed and is movable in guides 52 and 53 formed in the structure constituting the magazine chamber or an extension thereof.

The interior of the casing 21 has a supporting means for the ends of a stationary knife 54 which knife is stationed with its cutting edge in vertical alignment or nearly so, with the contacting surface of the rolls 43 and 44 so that the film fed between the rolls passes the cutting edge of the stationary knife and is in position to be cut when the movable knife 55 is carried into engagement or coaction with the stationary knife. In order to operate the movable knife, it is mounted on the spring arms 56 and 57 and said arms are slidably supported on the 90 guides 29, it being shown in the drawings that the arms have their ends remote from the knife 55 offset downwardly with respect to the other portions of the arms so that the knife is held slightly above the surfaces of 95 the guides 29 to permit a yielding action thereof when the movable knife travels under the stationary knife. The ends of the arms remote from the knife 55 are further provided with depending pins 58 and 59 respectively, which pins extend through slots 60 formed in the guides 29. The pins 58 and 59 are held in the slots by nuts 61 applied to the said pins under the guides 29 so that the said nuts prevent the pins from 100 withdrawing from the slots, but at the same time allowing free movement of the arm longitudinally of the guides.

The pins 58 and 59 are of such length that they extend into the path of travel of 110 the studs 62 and 63 projecting from the sides of the chains 40, so that movement of the chains is communicated to the knife when the studs encounter the pins.

As a means for operating the sprocket 115 chains, a shaft 64 is journaled transversely of the casing 21 and near each side of the casing a sprocket wheel 65 is mounted on the shaft, and each of said sprocket wheels engages one of the sprocket chains 40. Near 120 the opposite end of the casing 21, stub shafts 66 and 67 are journaled in the sides of the casing, one of which stub shafts being on each side. The stub shaft 66 has a sprocket wheel 68 and the stub shaft 67 125 has a sprocket wheel 69. The stub shaft 67 extends through the casing and has a crank handle 70 by which the stub shaft is turned. By reason of the connection of the sprocket chains with the sprocket wheels, turning of 130

the crank handle 70 will result in moving the sprocket chains in unison and as the blocks 33 and 34 are connected to the chain, motion of the chain is imparted to the blocks and consequently to the rod 32.

An arm 71 is mounted to freely rotate on one of the stub shafts and the arm has two lugs 72 and 73 spaced apart for receiving a stud 74 projecting from the side of one of the sprocket chains, so that as the sprocket chain moves backward and forward, the stud 74 engages one of the lugs 72 or 73 and partially rotates the arm 71 according to the direction of movement of the chain. A link 75 is provided for the arm 71 and has one end pivotally mounted on a stud 76 projecting from the face of the arm. The end of the link 75 remote from the arm is connected by a pivot 77 with the lever 78 which lever is mounted on a fulcrum 79. One side of the arm 71 has a pin 80 acting as a stop to limit the rotation of the arm so that the chain may rotate the arm only a predetermined distance.

The upper portions of the partitions 25 have bearings 80 and 81 for shafts 81^a and 82^a on which the arms 83 and 84 are respectively mounted. The shafts 81^a and 82^a have hangers 83^a and 84^a which are connected to an immersing frame 85 by pivots 86 so that as the arms swing, the immersing frame is moved with relation to the casing. A receptacle 87 is preferably placed in the casing and is designed to contain liquid such as a fixing fluid into which the film may be submerged by the immersing frame. The upper ends of the arms 83 and 84 are connected by a link 85^a so that motion communicated to one arm is communicated to the other arm and as the arms operate in unison for communicating motion to the immersing frame, it follows that film delivered to the receptacle 87 will be forced into the liquid. As a means for communicating the motion of the arm 71 to the immersing frame or the hangers supporting the same, the link 75 and the lever 78 hereinafter described are interposed between the arm 71 and the arms 84, but in addition to this link and lever just described, there is another element interposed between the lever and the arms 84 which it actuates, the said member comprising a slotted plate 88; the upper end of the lever 78 having a pivot 89 movable in the slot of the plate. The plate 88 has a recess 90 merging with the slot, the said recess forming a seat for the pivot 89 under certain conditions of operation. The plate is furthermore provided with a latch 91 mounted on a pivot 92 of the plate and the said latch has a shoulder 93 adapted to engage the pivot 89 so that movement of the lever 78 is communicated to the arm as the said lever oscillates. When the latch is moved from the

full line position shown in Fig. 9, to the dotted line position thereof, the lever may oscillate without communicating motion to the arm 84 in one direction.

When the latch 91 is out of engagement 70 with the pivot 89 the outward movement of the lever 78 is effective to lift the immersing frame, but the said frame instead of being positively actuated in its descent, is allowed to descend by gravity.

When the immersing frame is to be held in elevated position, as for instance, when film is removed from the receptacle, or for any other purpose the plate is adjusted with relation to the pivot 89 so that the said pivot 80 will lie in the recess or notch 90.

In order to guard the stationary knife 54 from the action of the fluids which might be displaced by the immersing frame, the arms 56 and 57 are provided with a supporting bar 94 and the said supporting bar carries a shield 95 which partially embraces the knife 54 as shown in Fig. 2; the said shield being carried from the stationary knife as the arms 57 are moved to cause the 90 movable knife to approach the stationary knife.

In the operation of the apparatus, the film 108, a length of which is projecting into the receptacle 41, is supposed to have been 95 exposed to the action of light and has been drawn from the exposing chamber and delivered to the said receptacle through the rotation of the feed rollers, heretofore described. Fig. 2 shows the first or initial position of the developing cutting and conveying apparatus and it will be seen that the rod 32 is normally stationed in front of the film 108 and that it is to be drawn rearwardly to engage the said film and draw it 100 from the receptacle 41 while the film is being held by the rollers 43 and 44, and thereafter, the said film is to be severed by the actuation of the movable knife with respect to the stationary knife. With this understanding of the mode of operation, rotation of the crank 70 will result in communicating motion to the shaft 64 through the medium of the sprocket chain on one side of the case 21 and through the rotation of the shaft 64, 110 115 the sprocket chain on the other side of the casing will likewise be moved to the same degree. As the crank 70 is to be moved in a clockwise direction initiatively, the rod 32 will be carried by the sprocket chains toward 120 the rear or right hand end of the apparatus as shown in Fig. 2, being thereby caused to engage the film and draw it from the receptacle 41. Upon movement of the sprocket chains the pin 74 of one chain engages the 125 lugs 72 and 73 of the arm 71 and partially rotates the said arm so that movement is communicated to the lever 78 and through such movement, the immersing frame 85 is lifted from the receptacle 87 and the hang- 130

ers 83^a and 84^a are elevated above the path of travel of the rod 32, thus permitting the said rod to carry the film over the said receptacle 87. The studs 62 and 63 which are 5 carried by the chain are in such relation to each other and to the other parts of the apparatus that one stud of each chain contacts a pin 58 or 59 and thereby the movement of the chains is communicated to the arms 56 10 and 57 which carry the knife 55 into engagement or coaction with the stationary knife so that the film is cut after it has been drawn by the rod 32 as stated.

The arm 71 is partially rotated by the 15 action of the chain, but in the travel of the chain, the pins 74 disengage the lugs 72 and 73 and continue to travel with the chain while allowing the arm to remain stationary with the parts in the position shown in Fig. 20 11 where the pin 80 is in engagement with the link serving to lock the parts against movement until such time as the chain is moved in an anti-clockwise direction, causing the return of the pin 74 into engagement 25 with the lugs 72 and 73 and a reversal of movement of the arm 71 so that the parts are again brought to the position shown in Fig. 2, it being understood that in the anti-clockwise movement of the chains, a stud engages 30 each of the pins 58 and 59 to move the arms 56 and 57 to the positions which they are shown to occupy in Fig. 2. After the parts have been brought to the position shown in Fig. 2, the film feeding or drawing rollers 35 are again operated to feed film into the receptacle and the operation is repeated.

As has been heretofore stated, it is possible to positively actuate the immersing frame through the action of the lever 78 by causing 40 the latch 91 to lock the pivots 89 in the end of the plate 88, but when the latch is in the position to release the pivot 89, the lever 78 moves the immersing frame in one direction only, that is to say elevates the 45 frame, whereas the frame is allowed to descend by gravity.

The magazine 20 is provided with any appropriate type of support for the spool 109 and as the type of spool is immaterial, it 50 is not described in detail.

The plate 88 has an apertured lug 110 in which an adjusting screw 111 is threaded, said adjusting screw having its end adapted to bear against the pivot 89 so that said 55 pivot may be held in the recess of the latch 91.

The receptacle 41 has hangers 112 extending downwardly to support a drip pan 113, the said drip pan being provided to receive 60 drippings of material discharged from the faucet 114 in the bottom of the receptacle 41, so that the said receptacle may be conveniently drained.

I claim—

65 1. In an apparatus relating to photogra-

phy, a receptacle for liquid to act on a film, means for delivering exposed film thereto, a member past which film travels to the receptacle, flexible means for moving the member to draw the film from the receptacle, and 70 means actuated in conjunction with the said member moving means for cutting the film.

2. In an apparatus relating to photography, means for drawing a web of film and to deliver it to a receptacle and for supporting the film therein, a rod past which the film travels to the receptacle, flexible means on which the rod is supported, means for moving the flexible means to draw film from the receptacle, a knife past which the 80 film travels in its delivery to the receptacle, a knife coacting therewith to cut the film, and means moved by the flexible means for actuating one of the knives.

3. In an apparatus relating to photography, a casing, a receptacle therein, means for delivering exposed film to the receptacle, a rod for moving film from the receptacle, guides in the casing, blocks slidable on the guides, said blocks having sockets 90 for the ends of the rod, means for moving said blocks on the guide, and means for cutting the film after it is removed from the receptacle.

4. In an apparatus relating to photography, a casing, a receptacle therein for receiving film, means for delivering film to the receptacle, means for drawing film from the said receptacle, a second receptacle in the casing over which the film is drawn, 100 means for cutting the film whereby it falls into the second mentioned receptacle, an immersing means operable with relation to the second mentioned receptacle, means for actuating the said immersing means, and flexible 105 means connected to operate the film drawing means and the film immersing means.

5. In an apparatus relating to photography, a casing, a receptacle therein, guides 110 in the casing, flexible means, means for drawing the flexible means longitudinally of the casing, a film drawing means connected to the flexible means, means for delivering film to the receptacle and for suspending it while the film drawing means operates to remove the film from the receptacle, a second receptacle in the casing over which film is suspended by the film drawing means, means for severing the said film to permit it to fall into the second mentioned receptacle, film immersing means suspended above the second mentioned receptacle and adapted to coact therewith, and means actuated by the flexible means for operating the 120 immersing means.

6. In an apparatus relating to photography, a casing, a receptacle therein, means for delivering film to the said receptacle and for supporting it, guides in the casing, flexi- 125

ble members operating over the guides, blocks engaged by the said guides, a film drawing member supported by the blocks and movable therewith, and means for moving the flexible members, a stationary knife and a movable knife adapted to coact therewith, arms on which the movable knife is mounted, said arms being supported by the guides, and means whereby the flexible members communicate motion to the said arms for moving the knife into engagement with the stationary knife.

7. In an apparatus relating to photography, a casing, a receptacle therein, means for delivering film to the said receptacle and for supporting it, guides in the casing, flexible members operating over the guides, blocks engaged by the said guides, a film drawing member supported by the blocks and movable therewith, means for moving the flexible members, a stationary knife, a movable knife adapted to coact therewith, arms on which the movable knife is mounted, said arms being supported by the guides, means whereby the flexible members communicate motion to the said arms for moving the movable knife into engagement with the stationary knife, a second receptacle in the casing over which the film is drawn by the film drawing means and into which it falls when cut, immersing means suspended above the second mentioned receptacle, means for actuating the immersing means consisting of a disk actuated by the flexible means, a link moved by the disk, a lever connected to and actuated by the said link and a member interposed between the lever and the said immersing means.

8. In an apparatus relating to photography, a casing, a receptacle therein, means for delivering film thereto, arms pivotally supported in the casing above the said receptacle, an immersing frame suspended from the arms and adapted to enter the receptacle, means for causing the arms to move in unison, a slotted plate pivotally connected to one of the arms, a lever having a pivot in the slot of the plate, and means for actuating the lever for communicating motion to the plate.

9. In an apparatus relating to photography, a casing, a receptacle therein, means for delivering film thereto, arms pivotally supported in the casing above the said receptacle, an immersing frame suspended from the arms and adapted to enter the receptacle, means for causing the arms to move in unison, a slotted plate pivotally connected to one of the arms, a lever having a pivot slideable in the slot of the plate, means on the plate adapted to prevent movement of the said pivot with relation to the plate for positively moving the plate as the lever moves, and means for actuating the lever.

10. In an apparatus relating to photog-

raphy, a casing, a receptacle therein, means for delivering film thereto, arms pivotally supported in the casing above the said receptacle, an immersing frame suspended from the arms and adapted to enter the receptacle, means for causing the arms to move in unison, a slotted plate pivotally connected to one of the arms, a lever having a pivot slideable in the slot of the plate, a latch for temporarily preventing movement of the pivot with relation to the plate when the motion is to be communicated to the plate, said plate having a recess for engaging the pivot for holding the immersing means elevated, and means for operating the lever.

11. In an apparatus relating to photography, a casing, a receptacle therein, means for delivering film thereto, arms pivotally supported in the casing above the said receptacle, an immersing frame suspended from the arms and adapted to enter the receptacle, means for causing the arms to move in unison, a slotted plate pivotally connected to one of the arms, a lever having a pivot, said plate having a recess forming a notch for the reception of the pivot of the lever whereby the immersing frame is held elevated.

12. In an apparatus relating to photography, a casing, receptacles therein, means for delivering film to one of the receptacles, and supporting it therein, a member adapted to draw films from one of said receptacles and suspend it over another receptacle, blocks for carrying the said drawing member, guides in the casing on which the blocks are slideable, flexible members for moving the blocks longitudinally of the casing, arms slidably mounted on the guides of the casing, a knife carried by the said arms, a knife with which the first mentioned knife coacts, means associated with the flexible members for actuating the arms carrying the knife, a disk mounted to rotate in the receptacle, means on the disk for receiving motion from the flexible member whereby the disk is partially rotated, a link pivoted to the disk, a lever actuated by the link, a stop pin on the disk adapted to engage the link when the said disk is rotated a predetermined distance, means for operating the flexible means whereby the said flexible means may be caused to travel in alternate directions for moving the film drawing means and said disk alternately in opposite directions, and an immersing means operated by the lever.

13. In an apparatus relating to photography, a casing, guides therein, blocks slideable on the guides, a film drawing member carried by the blocks, flexible members, rotating members mounted in the casing over which the flexible members are operated, means for turning the rotating members in opposite directions for moving the flexible members longitudinally of the casing, said

- 6
- guides having slots therein, arms supported by the guides and having studs projecting through the slots, means on the flexible members adapted to engage the studs for communicating motion to the arms, a knife carried by the arms, a stationary knife in conjunction with which the first mentioned knife operates, arms pivotally mounted in the casing, a receptacle into which the said arms extend, an immersing member carried by the said arms, means for connecting the arms to cause them to move in unison, a slotted plate pivotally connected to one of the arms, a lever pivoted in the casing and adapted to actuate the said plate, and means for holding the plate in adjusted relation to the said pivot whereby the immersing frame is held out of the said receptacle. 35
14. In an apparatus relating to photography, a casing, guides therein, blocks slideable on the guides, a film drawing member carried by the blocks, flexible members, rotating members mounted in the casing over which the flexible members are operated, 40 means for turning the rotating members in opposite directions for moving the flexible members longitudinally of the casing, said guides having slots therein, arms supported by the guides and having studs projecting through the slots, means on the flexible members adapted to engage the studs for communicating motion to the arms, a knife carried by the arms, a stationary knife in con- 45
- junction with which the first mentioned knife operates, arms pivotally mounted in the casing, a receptacle into which the said arms extend, an immersing member carried by the said arms, means for connecting the arms to cause them to move in unison, a slotted plate pivotally connected to one of the arms, a lever pivoted in the casing and adapted to actuate the said plate, a disk mounted to rotate in the casing, a link connected to the plate and to the lever whereby movement of the link is communicated to 50 the lever, lugs on the disk, means projecting from one of the flexible members for communicating motion to the disk, whereby the said disk is alternately rotated in opposite directions, and means on the disk for limiting the rotary motion of the disk. 55
15. In an apparatus relating to photography, a casing, a receptacle therein, means for delivering exposed film to the receptacle, guides in the casing, blocks slideable in the guides, means carried by the blocks for removing film from the receptacle, means for moving said blocks on the guides, and means for cutting the film after it is removed from the receptacle. 60

In testimony whereof, I affix my signature in the presence of two witnesses.

GEORGE C. BEIDLER.
